UNITED STATES PATENT OFFICE

2,669,141

SLIDING JAW SCREW CAP JAR WRENCH

Edgar B. Davis, Tangerine, Fla.

Application June 29, 1951, Serial No. 234,214

13 Claims. (Cl. 81—3.42)

1

This application is a continuation in part of my co-pending application Serial No. 153,187, filed March 31, 1950, now abandoned.

This invention relates to a screw cap jar opener, and more particularly to a screw cap jar opener of the kind to be more particularly described hereinafter having means for limiting the clamping action of the jar opener on the screw cap in a manner to prevent the breaking of the jar upon an application of an excess force being applied to the screw cap.

It has for one object to provide a screw cap jar opener having a yieldable, resilient, pawl member for positioning the movable clamping jaw member in clamping engagement with a screw cap to be removed from a glass jar, the yieldable pawl member being bendable upon application of an undue force exerted on the handles of the screw cap opener to prevent the accidental breaking or cracking of the glass jaw on which the cap is engaged.

Another object of the invention is to provide an automatic, self-adjusting, built in flexibility in the screw cap jar opener in order to provide a jar opener which is safe for a user when removing caps from glass jars and no severe crushing effect will be applied to the cap when removing or applying plastic and thin metal caps.

Another object of the invention is to provide a screw cap jar opener having a minimum number of effective parts operatively connected together to provide a screw cap jar opener of this kind resulting in lower production costs for the device which in turn leads to the lower price of the device for the consumer.

Another object of my invention is to provide in connection with a wrench having opposed handles and means actuated by the opposed handles to draw opposed jaws together wherein if excessive pressure is applied to the handles, the jaws together of the jaws thereby is sharply and suddenly limited to prevent the application of excess pressure on the object being handled.

While I have illustrated my invention as applied to a jar opener, it will be obvious it may equally well be applied to any other device where two jaws are brought together to grip an object.

My invention is illustrated more or less diagrammatically in the accompanying drawings; wherein:

Figure 1 is a top plan view of a screw cap jar opener;

Figure 2 is a side elevation;

Figure 3 is a fragmentary, horizontal, longitudinal section taken on the line 3—3 of Figure 2;

2

Figure 4 is a transverse section taken on the line 4—4 of Figure 3;

Figure 5 is a transverse section taken on the line 5—5 of Figure 3;

Figure 6 is a fragmentary, detailed side elevation, partly broken away, showing the engagement of the pawl with the serrated or toothed edge of the bar;

Figure 7 is a bottom plan view of a modified form of the device;

Figure 8 is a section along the line 8—8 of Figure 7;

Figure 9 is a partial top plan view of a part of the device shown in Figure 7;

Figure 10 is a detail view similar to Figure 7 showing the parts in a different position;

Figure 11 is a plan view in part section similar to Figure 10 showing the parts in a further stage of compression;

Figure 12 is a section along the line 12—12 of Figure 8;

Figure 13 is a section along the line 13—13 of Figure 8;

Figure 14 is a view similar to Figure 10 showing final gripping position; and

Figure 15 is a separate plan view of the wrench body.

Like parts are indicated by like characters throughout the specification and drawings.

Referring to the drawings, the numeral 10 designates generally a safety screw cap jar opener constructed according to an embodiment of my invention. The screw cap jar opener 10 is adapted to be clampingly engaged with a metal screw cap 11 engaged on the upper threaded end 35 of a glass bottle or jar, as the cap of glass canning jars generally and popularly in use. In order to prevent the crushing of the screw cap 11 to the point of snapping or cracking the glass jar, the screw cap jar opener 10 is provided with a yieldable means engaging the movable clamping jaw for releasing the movable clamping jaw from its engagement with the screw cap 11 upon the application of a predetermined, undue force.

The screw cap jar opener 10 is formed with a longitudinally extending, flat bar member 12 having a fixed jaw member 14 fixed to, or formed integrally with, one end thereof. The opposite side edges 15 and 16 of the bar 12 may be serrated or formed with closely spaced apart, small, 40 ratchet teeth 17 with which a pawl member, to be more specifically described hereinafter is adapted to be engaged.

A wrench body 18 is slidably engaged on the bar 12 for sliding movement along the length thereof. The wrench body 18 is formed of a flat

sheet of metal bent at its forward end in a manner to provide a sliding channel member 19 on the upper side of the forward edge thereof for overlying the upper edge 15 of the elongated bar 12. A similar, confronting channel member 20 is formed on the opposite side edge of the front portion of the wrench body 18 and is adapted to slidably engage over the lower edge 16 of the longitudinally extending bar 12 for slidably supporting the wrench body 18 thereon. The channel members 19 and 20 extend only a short distance rearwardly from the extreme forward edge of the wrench body 18, and the rear portion of the wrench body 18 is flattened out to form an upwardly extending arm 21 and a depending arm 22, as clearly noted in Figure 4 of the drawings. The upwardly extending arm 21 will form a pivot member for supporting an upper pivot pin 24 and the depending arm 22 will form a journal below the lower edge of the bar 12 for the lower pivot pin 25.

A movable or slidable clamping jaw member 26 is slidably supported on the bar 12 and is slidably engaged between the channel members 19 and 20 and the bar 12 for slidably supporting the movable jaw member 26 within the wrench body 18 in the manner clearly noted in Figure 5 of the drawings. The movable jaw member 26 is slidably carried by the wrench body 18 for extension and retraction therefrom, in a manner to be more particularly described hereinafter. At the rear end of the slideable jaw member 26 there is formed a laterally extending abutment member 27 which is adapted to be engaged by the handle of the jaw opener for sliding the movable jaw member 26 forwardly from the wrench body 18 for clamping engagement with a screw cap, as the screw cap 11, which screw cap will be clamping engaged between the fixed jaw member 14 and the movable jaw member 26.

An upper handle 28 is pivotally mounted at one end on the upper pivot pin 24, and a lower, confronting handle 29 is pivotally mounted on the lower hinge pin 25, as clearly noted in Figures 1 and 3 of the drawings. Each of the handles 28 and 29 is formed of a sheet of metal bent upon itself to define a pair of longitudinally extending, channel-shaped handle members open on the confronting sides thereof.

A depending lever arm 30 is formed on the upper handle member 28 extending downwardly a considerable distance below the upper pivot pin 24 and an upwardly extending lever arm 31 is formed integrally with the lower handle member 29 extending upwardly therefrom to a point slightly spaced from the longitudinal median of the bar 12. The upper lever arm 30 is formed with a cut out portion 32 on the lower edge thereof and the upwardly extending lever arm 31 is formed with an upwardly opening cut out portion 34 on the upper end thereof defining therebetween a recess within which the outwardly extending abutment member 27 carried by the movable jaw member 26 is adapted to be engaged for connection to the pivotally mounted handles 28 and 29, clearly noted in Figures 3 and 4 of the drawings.

An upper, resilient pawl member 35 is carried by the upper handle member 28, and a lower, resilient and yieldable pawl member 36 is carried by the lower handle member 29 for tensioning the movable clamping jaw 26 into clamping engagement with a screw cap 11 upon pivoting the handles 28 and 29 together about the respective pivots 24 and 25.

The upper, resilient and yieldable pawl member 35 is formed of a short length of wire which is coiled about the upper pivot pin 24 and has one end thereof engaged in the handle 28 and extending a short distance along the length thereof. The other end 39 of the pawl member 35 extends downwardly and rearwardly from the pivot pin 24 to be engaged between the teeth 17 on the upper edge 15 of the bar 12 upon swinging of the upper handle 28 downwardly about the pivot pin 24 into a position substantially parallel to the bar 12. The lower, yieldable pawl member 36 is formed in substantially the same manner as the upper, yieldable pawl member 35 of a short length of flat wire at least partially coiled about the lower pivot pin 25 and having one end extending longitudinally a short distance along the length of the lower handle 29. The other end of the lower pawl member is provided with a point 40 for engagement between the teeth 17 on the lower edge 16 of the bar 12. Being of a resilient and springy nature, the pawl members 35 and 36 also act as resilient spring means for biasing the handles 28 and 29 apart into a divergent, normal relation about the pivot pins 24 and 25 in the open position of the screw cap jar opener.

As the lever members 30 and 31 of the handles 28 and 29, respectively, engage the outwardly extending abutment member 27 of the movable jaw member 26 upon pivoting of the handles 28 and 29 together about their respective pivots, the respective pawls 35 and 36 will initially engage the serrated or toothed edges of the central bar 12 for holding the handles and movable jaw member against sliding in one direction thereon. Further pivotal movement of the handles together will effect the forward swinging movement of the levers 30 and 31, whereupon the movable jaw member 26 will be slidably moved forwardly from its engagement in the wrench body 18 to a clamping position for engaging a screw cap 11 between the fixed clamping member 14 and the movable jaw member 26. Upon the application of an undue force on the handles 28 and 29 for pressing the movable jaw member 26 forwardly, the rearward inclination of the resilient pawl members 35 and 36 will provide for the release of the pawl from the respective edges of the bar 12 so that no undue force may be applied to the handles 28 and 29 for pressing the movable jaw member 26 into engagement with a screw cap 11 with a force sufficient to crack the glass jar on which the cap is mounted.

For removing the screw cap jaw opener from its engagement with the screw cap 11, the handles 28 and 29 may be moved divergently about their respective pivot pins for disengaging the respective pawls 35 and 36 and providing for the free sliding movement of the wrench body 18 and movable jaw member 26 rearwardly along the length of the bar 12 out of engagement with the cap 11.

In order to hold the handles 28 and 29, together with the wrench body 18 and the movable jaw member 26, on the bar 12, an abutment member or detent 41 is formed on the end of the bar 12 remote from the fixed clamping jaw 14 for engagement with the wrench body 18 in the most rearward position of the wrench body and the handles 28 and 29.

While the terms "upper" and "lower" have been used in the application to define the handle members 28 and 29, it will be understood that such a description is used merely in reference to the drawings to clearly denote these mem-

bers; but it will be understood that in the general use of a device of this kind, the handles 28 and 29 will be disposed in a horizontal, side by side, relation.

In the embodiment of Figures 7 to 14, 50 is a wrench body. It encloses a fixed jaw plate 51, laterally projecting from it is an inner jaw 52. The wrench body also encloses an adjustable jaw bar 53 from which projects laterally a jaw 54 in opposition to the jaw 52. The fixed jaw plate 51 and the adjustable jaw bar 53 are held in slidable relationship with one another and with the wrench body 50 by the flanges 55, 56 which are integral with the wrench body, the plate 51 and bar 53 being slidable one with respect to the other but constrained by the wrench body to parallel movement. 57, 58 are pivot arms extending laterally from the wrench body 50. Handles 59 and 60 enclose the pivot arms 57, 58 and are pivoted on said arms. Extending inwardly from the handles 59 and 60 are clamping levers 61, 62; each lever terminating in a slot 63, 64, the slots being narrow at the ends of the lever arms but of greater size further in for clearance. 65 is a driving lug integral with the jaw plate 51 so that when the handles 59 and 60 are drawn together, the levers 61 and 62 move to the left, in Figure 7 and in view of their interlocking with the lug 65; they cause a forward movement of the jaw plate 51 and jaw 52 with respect to the wrench body.

66 is a spring associated with the handle 59 and the pivot arm 57, biasing the handle 59 to open position and because the handle 59 is connected to the handle 60 through the lug 65 and the lever arm 61 and 62; the spring 66 also biases the handle 60 to open position.

The jaw bar 53 is serrated as at 67 along one edge. In opposition to this serrated edge is a dog 68 having a plurality of teeth adapted to mesh with the serration 67; the teeth on dog and bar being of the same contour. The dog 68 is pivoted concentric with the handle 60 on the pivot arm 58. 69 is a spring anchored on the handle 60 at one end and at the other end permanently attached to the dog 68 so that when the parts are in the position shown in Figure 7 with the handles in open position the dog 68 is out of contact with the serrated edge or rack on the jaw bar 53. Under these circumstances, when the parts are in the position shown in Figure 7, the user is free to move the sliding bar 53 back and forth within the wrench body to adjust manually the distance between the wrench jaws 52, 54. They may be brought so closely together that they touch or they may be brought so far apart that the stop member 70 on the bar 53 engages the jaw plate 51 to limit further movement, all this without any movement of the handles whatever.

When the wrench is to be used, the two jaws 52 and 54 are brought against opposed sides of the jar top or other object to be opened or turned by sliding 53 in 50 which can easily be done because the dog is out of contact with the sliding bar. Then the user squeezes the two handles together, a very slight rotation brings the dog into engagement with the serrated edge of the sliding bar. Further rotation of the handles tends to move the fixed jaw plate outwardly in the wrench body, forcing the fixed jaw 52 outwardly toward the adjustable jaw 54 and causing the two jaws to grip the object held between them. This further movement may continue until the levers 61, 62 engage the flanges 55 on

the wrench body at which time no further rotary movement of the handle about their pivot in the closing direction is possible.

In view of the fact that the wrench is intended to be used to unscrew delicate or thin screw caps on glass bottles and jars, it will be obvious that excess pressure brought by the user on the handles might crush the caps and even crush the jars so the interlock between the dog 68 and the teeth 67 is not a positive one. The teeth are slanted teeth. They are held together by the pressure of the spring 69. If the force drawing the jaws 52 and 54 together becomes too strong, the user having pressed too hard on the handles, the dogs will slip one notch, the spring 69 being compressed sufficiently to allow the dog teeth to slide out and engage the tooth bar one tooth further back. The arrangement and relation of the parts is such that under ordinary circumstances one tooth movement is all that is permitted. Further movement is prevented because of the limiting contact of the levers 61, 62 with the lugs 56.

The spring 69 works both ways. It holds the dog 68 against the teeth 67 when the handles 59 and 60 are brought together but it positively draws the dog 68 away from the teeth 67 when the spring 66 is allowed to open the handles, thus making it easy for the user to adjust the jaws back and forth to fit the size of jar or other object being treated without interference by the teeth of dog and adjusting bar.

It is essential that the relationship between the two jaws and the handles be such that no matter how hard the operator squeezes on the handles he will not crush and break the bottle. The stops 56 limit the movement of the levers 61 and 62 and so limit the maximum movement of the jaw 52 toward the jaw 54. This limitation is present whether the dog 68 is able to jump one tooth on the member 53 or not and the provision which permits jumping of a single tooth merely is an added safeguard against crushing the glass jar. The essential thing is that no matter how they work, means are provided which effectively prevent such movement of jaw 52 toward jaw 54 as would be sufficient to crush the glass against the jar and break the jar. Slight movement is essential to grip the cap. Excessive movement would break the jar and such excessive movement is effectually avoided in my invention.

I claim:

1. A jar opener comprising an elongated bar having a jaw on one end, a body member slidable on said bar, a jaw member slidably in said body member, a pair of opposed handles pivoted on said body member, a lever arm on each of said handles engaging said jaw member for sliding said jaw member in the direction of the jaw on the bar, and a pawl member carried by each handle engageable with said bar for releasably positioning said jaw member on said bar upon pivoting said handles together for clampingly engaging a jar cap between the jaw and said jaw member, engageable means on said elongated bar for reception of said pawl so as to provide firm contact therebetween, said pawl members being releasable from said bar upon separating said handles for removing the jar from the cap engaged thereby.

2. A jar opener for a jar having a screw cap comprising an elongated bar having a jaw member fixed thereon, a body member slidable on said bar, a second jaw member slidable on said body

member, a handle pivoted on said body member and engaging said slidable jaw member, and a resilient pawl member carried by said handle for engagement with said bar for sliding said movable jaw member in the direction of said fixed jaw member upon rocking said handle on said body member.

3. A jar opener for a jar having a screw cap comprising an elongated bar having a jaw member fixed thereon, a body member slidable on said bar, a second jaw member slidable on said body member, a pair of handles pivoted on said body member and engaging said slidable jaw member, and a resilient pawl member carried by each of said handles for engagement with said bar for sliding said movable jaw member in the direction of said fixed jaw member upon rocking of said handles together on said body member.

4. A wrench including a wrench body, a pair of handles pivotally mounted thereon for movement toward and from one another, means biasing said handles to the open position, a short, carrying slide member slidably mounted in the body having a jaw projecting therefrom at right angles to the plane of the handles, one of the handles having a lever rotatable therewith, a lug projecting from the short slide member engaging the lever whereby movement of the handles toward one another forces the jaw on the short slide member away from the body, a long adjustable jaw carrying member slidable in the body having a jaw in opposition to the first-mentioned jaw, the edge of the adjustable member being serrated, a dog pivoted on the wrench body, and a connection between the dog and one of the handles whereby movement of the handles toward one another causes the dog to engage the serrations.

5. A wrench including a wrench body, two parallel jaw carrying members slidable therein, a jaw on each in opposition to the other, handles pivoted on the wrench body for movement toward and from one another, means biasing the handles to the open position, one jaw member being adjustable in the body, means between the said one jaw member and at least one handle for locking the said one jaw member against movement in one direction when the handles are actuated, a driving connection between the other jaw member and one of the handles whereby movement of the handle causes the jaws to approach one another.

6. A wrench including a wrench body, two parallel jaw carrying members slidable therein, a jaw on each in opposition to the other, handles pivoted on the wrench body for movement toward and from one another, means biasing the handles to the open position, one jaw member being adjustable in the body, a driving connection between the other jaw member and one of the handles whereby movement of the handle causes the jaws to approach one another, means interposed between said one jaw member and one of the handles to lock such member against movement with respect to the body as the handles approach one another.

7. A wrench including a wrench body, two parallel jaw carrying members slidable therein, a jaw on each in opposition to the other, handles pivoted on the wrench body for movement toward and from one another, means biasing the handles to the open position, one jaw member being adjustable in the body, means between the said one jaw member and at least one handle for locking the said one jaw member against move-

ment in one direction when the handles are actuated, a driving connection between the other jaw member and one of the handles whereby movement of the handle causes the jaws to approach one another, the driving connection including a lever on one of the handles and interlocking means interposed between it and the jaw.

8. A wrench including a wrench body, two parallel jaw carrying members slidable therein, a jaw on each in opposition to the other, handles pivoted on the wrench body for movement toward and from one another, means biasing the handles to the open position, one jaw member being adjustable in the body, means between the said one jaw member and at least one handle for locking the said one jaw member against movement in one direction when the handles are actuated, a driving connection between the other jaw member and one of the handles whereby movement of the handle causes the jaws to approach one another, the driving connection including a slotted lever on one of the handles, a lug integral with the jaw member extending perpendicular from one side thereof and interlocking with the slot in the lever.

9. A wrench including a wrench body, two parallel jaw carrying members slidable therein, a jaw on each in opposition to the other, handles pivoted on the wrench body for movement toward and from one another, means biasing the handles to the open position, one jaw member being adjustable in the body, a driving connection between the other jaw member and one of the handles whereby movement of the handle causes the jaws to approach one another, means interposed between said one jaw member and one of the handles to lock such member against movement with respect to the body as the handles approach one another, the jaw member locking means including a plurality of serrations on the jaw member, a dog pivoted on the wrench body and a driving connection between one of the handles and the dog whereby closing movement of the handles causes engagement of dog and serrations.

10. A wrench including a wrench body, two parallel jaw carrying members slidable therein, a jaw on each in opposition to the other, handles pivoted on the wrench body for movement toward and from one another, means biasing the handles to the open position, one jaw member being adjustable in the body, a driving connection between the other jaw member and one of the handles whereby movement of the handle causes the jaws to approach one another, means interposed between said one jaw member and one of the handles to lock such member against movement with respect to the body as the handles approach one another, the jaw member locking means including a plurality of serrations on the jaw member, a dog pivoted on the wrench body and a driving connection between one of the handles and the dog whereby closing movement of the handles causes engagement of dog and serrations, the driving connection including a flexible element which can yield to permit limited movement of the dog along the serrated surfaces.

11. A jar opener for a jar having a screw cap comprising an elongated serrated bar having a jaw member fixed thereon, a wrench body slidably on said bar, a second jaw member slidable on said wrench body, a pair of handles pivoted on said wrench body and engaging said slidable jaw member, and a resilient pawl member carried by each of said handles for engagement with

the serrated portion of said bar for sliding said movable jaw member in the direction of said fixed jaw member upon rocking of said handles together on said wrench body, the resiliency of the pawl member being such as to release its hold on the bar to permit limited movement of the jaw members relative to each other upon excessive clamping pressure of the jaw members against a screw cap to be removed.

12. A jar opener for a jar having a screw cap comprising an elongated serrated bar having a jaw member fixed thereon, a wrench body slideable on said bar, a second jaw member slideable on said wrench body, a pair of handles pivoted on said wrench body and engaging said slideable jaw member, and a yieldable resilient pawl member carried by each of said handles for engagement with the serrated portion of said bar for locking said slideable jaw member from movement in a direction away from said fixed jaw member upon rocking of said handles together on said wrench body, said pawl being yieldable upon application of a predetermined clamping force applied on said movable jaw member for clamping a jar cap between said jaw members.

10

13. A jar opener for a jar having a screw cap comprising an elongated serrated bar having a jaw member fixed thereon, a wrench body slideable on said bar, a second jaw member slideable through said wrench body, a handle pivoted on said wrench body and engaging said slideable jaw member, and a resilient pawl member carried by said handle for engagement with the serrated portion of said bar for locking said wrench body against movement with respect to the said fixed jaw member upon rocking said handle on said wrench body, the resiliency of the pawl member being such as to release its hold on the bar to permit limited movement relative to the bar upon the application of excessive clamping pressure.
